UNITED STATES PATENT OFFICE

2,098,173

EXCAVATING AND HOISTING MACHINE

George E. Baldry, Winnipeg, Manitoba, Canada

Application January 2, 1937, Serial No. 118,885
In Canada November 21, 1935

10 Claims. (Cl. 255—23)

The invention relates to excavating and hoisting machines and an object of the invention is to provide a compact, portable and easily controlled power driven machine for carrying out 5 the major part of the work entailed in underpinning the walls of a building according to the method disclosed in Patent Number 1,979,670 of the United States of America, dated the sixth day of November 1934.

10 A further object of the invention is to arrange certain parts of the machine so that an attendant located adjacent the front end of the machine and within view of the excavation being made, by the machine, can control with facility from 15 such point, the entire operation of the machine.

A further object is to design the parts so that 20 they can be manufactured and assembled at comparatively small cost and such that the required work can be done accurately, effectively and with dispatch.

25 A further object is to construct a portable machine, embodying a boring unit, a hoist and a prime mover, all interconnected and under the selective control of a single attendant and to 30 so locate such major parts that they can effectively function without interference one with the other, to carry out the work for which they were designed.

35 A further object is to locate the boring unit at the front end of the machine so that it can be brought near the wall underneath which the underpinning is to be done and to mount the boring unit so that it can be adjusted to the angular position best suited for the driving of the boring 40 tool in the working position of the latter underneath the wall footing.

45 A further object is to provide the hoist with a vertically adjustable and laterally moveable boom, clear of the boring unit, and carrying a pair of winding cables one of which is up when the other is down, such arrangement permitting of the ready successive liftings of the earth loaded tool from the excavated hole and of the easy disposition of the earth carried by the tool in a location to the side away from the work.

50 A further object is to construct certain parts of the boring unit so that the jointed line leading to the boring tool can be easily and quickly freed from the machine at the time it is desired to utilize the hoist to raise the earth loaded tool and further to design the several similar universal joints connecting the several rods or sections of the line so that they can be easily and quickly 55 disconnected to permit of the insertion of an ad-

ditional rod length in the line, each time the dug earth is removed from the boring tool.

A further object is to arrange the worm wheel 5 for driving the boring tool, so that the upper driving section of the line, can slide therethrough whilst being driven, and also to provide a bearing for centering the worm wheel in the working position of said wheel and a releasable yoke bar for retaining the worm wheel seated on the bearing during the boring operation and which permits of the easy removal of the worm wheel from the driving section of the line as and when required.

A further object is to provide a pile weight or 10 hammer for use with the hoist when it is desired 15 to drive piles into the ground.

With the above more important and other minor objects in view which will become more apparent as the description proceeds, the invention consists essentially in the arrangement and 20 construction of parts hereinafter described reference being had to the accompanying drawings, in which

Fig. 1 is a side view of the machine showing, generally, its position in relation to the wall under which the concrete pile is to be placed. In this view however, the boom would require to be moved from the position shown in full outline to the position appearing in dotted outline to place it in working position in regard to the wall shown.

Fig. 2 is an enlarged detailed side view of the hoist mechanism.

Fig. 3 is a plan view of the parts appearing in Fig. 2.

Fig. 4 is an enlarged detailed side view of the 35 boring tool drive unit.

Fig. 5 is a plan view of the parts appearing in Fig. 4.

Fig. 6 is a front view of the worm wheel and associated parts, the yoke bar and base plate being broken away.

Fig. 7 is a vertical sectional view at 7—7 Fig. 5 certain parts being omitted.

Fig. 8 is a plan view of the front end of the boom.

Fig. 9 is a perspective view of the central part of the mast cross bar.

Fig. 10 is a front face view of the bearing for the boom.

Fig. 11 is a vertical sectional view at 11—11 50 Fig. 1 part of the vertical side member of the mast being broken away.

Fig. 12 is a perspective view of the boring tool.

Fig. 12^A is an enlarged detailed plan view of 55

the universal joint used to connect the several sections or rods of the line.

Fig. 13 is a plan view of the split ring employed.

Fig. 14 is a side view of the pile weight or ham-
5 mer.

Fig. 15 is a side view of a modified form of the machine, part of the mast and boom being broken away.

Fig. 16 is a plan view of the parts appearing in
10 Fig. 15, and with the driving unit for the boring tool swung down to the horizontal position.

In the drawings like characters of reference indicate corresponding parts in the several figures.

The main frame 1 of the machine comprises
15 similar parallel suitably spaced side beams 2 and
2' connected by front and rear cross beams 3 and
3' and supporting a rearwardly disposed bed plate
4 securely fastened to the beams. The beam 3'
is set in somewhat from the front end of the
20 frame to clear the boring tool line should the
same be working vertically. In advance of the
bed plate 1 locate a further cross beam 5 utilized
to carry the boom later described.

An electric motor 7 or other prime mover, is
25 mounted rearwardly on the bed plate and the
motor shaft 7' carries the pulley 8. The bed plate
has also permanently mounted thereon a re-
versible hoist, indicated generally by the refer-
ence numeral 9 and described in detail herein-
30 after.

Directly in advance of the hoist I have located
a mast 10, which comprises similar opposing up-
rights 11 having their upper ends connected by
35 a cross bar 12 and their lower ends attached by
pivot bolts 13 to side plates 14 firmly secured to
the side beams of the frame. The mast can be
swung rearwardly when not in use. The mast is
fastened to the rear corners of the frame by simi-
40 lar tie rods 15 provided with turn buckles 15' for
adjusting purposes. The cross bar 12 is supplied
centrally and in its rear edge, with a notch or
slot 12' (see Fig. 9) to receive the boom chain
later referred to.

The beam 5 is positioned slightly ahead of the
45 mast, and receives centrally of its length, a pivot
pin 16 carried by a disc or head 16' the head being
supplied with similar spaced lugs 17' carrying a
horizontally disposed pin 17. The pin 17 pivotally supports the lower end of the boom 18 and
50 accordingly the boom can be raised vertically
or swung laterally as desired. The free end of
the boom carries a pair of spaced side arms 18
and 18' which support the spindles 19 and 19'
55 of similar pulleys 20 and 20' located between the
arms. Bowed side bars 21 are secured to the arms
and carry a cross pin 22 to which I attach the
forward end of the boom supporting chain 23.
The rear end of the chain is caught in the slot
60 12' and obviously I can adjust the boom in a
vertical direction by catching one or other of
the chain links in the slot in the well known man-
ner.

The forward end of the main frame has perma-
65 nently secured thereto two similar upstanding
side plates 24 and 24' which provide pivot bear-
ings for the adjustable driving unit 25, utilized
for driving the line of rods or sections 26 leading
to the boring tool.

The hoist previously mentioned is now de-
70 scribed in detail. Two similar side standards 27
and 27' are provided and these are securely bolted
to the base plate and they provide suitable bear-
ings for the various cross shafts now described.
Spacers 28 extend between the standards to lend
75 rigidity to the structure. The main drive shaft

of the hoist, indicated at 29, is provided between
the standards with a pinion 29' and in a location
aligned with the motor pulley, with a pulley 30
connected by a belt 31 to the motor pulley. The
pulley 30 is rotatably mounted on the shaft 29
and is associated with an internal friction clutch
32 of well known design and not herein described
in detail. The clutch embodies a pivoted actu-
ating lever 33 which has its free end continuously
riding a cone pulley 34 feathered on the shaft 10
and moveable endwise therein. Provision is made
for shifting the cone pulley to swing the lever,
and in the arrangement as shown, the out move-
ment of the cone pulley, effects through the in-
15 cident outshifting of the free end of the lever,
the coupling of the pulley 33 to the shaft 29. In
the position of the parts shown, the pulley is free
to rotate on the shaft.

To shift the cone pulley I have herein pro-
vided a forked arm 35 which spans the cone pulley 20
in the usual way and have mounted the arm on a
spindle 36 carried by suitable bearings 36' se-
cured to the side standards. A side bar 37 is piv-
otally secured to bracket 38 carried by one of the
25 side plates 14 and the rear end of the side bar is
provided with a fork 37' spanning the spindle 36
and connected thereto by a pin 39. The forward
end of the bar 37 is suitably attached to a con-
trol lever 40 carried by the main frame and lo-
cated near the front end of the machine. Ob-
viously the shifting of the lever in the proper di-
30 rection will engage or disengage the clutch.

The pinion 29' meshes continuously with a gear
41 secured to the countershaft 41' carried by the
standards and the countershaft carries also a
35 pair of spaced pinions 42 and 42' and a chain
wheel 42'. The pinion 42 meshes continuously with
a relatively wide pinion 43 carried by a stub shaft
43' secured to the standard 27 and the pinion 42'
40 is adapted to be engaged by a shiftable gear 44
feathered on a cross shaft 44' carried by the stand-
ards. The gear 44 is also adapted when shifted
in the proper direction to engage the pinion 43.
Accordingly by shifting the gear 44 I can drive
the shaft 44' in a forward or reverse direction. 45
The latter gear is engaged by a spanning fork
45' carried by an overlying spindle 45 mounted
in the standards, and the latter spindle is end
shifted by a pivoted side bar 46 and a control
lever 47 arranged in substantially the same man-
50 ner as those previously described. The levers
are mounted side by side so that they can be con-
veniently actuated by the attendant.

The shaft 44' has secured thereto a pinion 48
55 which meshes continuously with a gear 49 se-
cured to a further countershaft 49' carried by
the standards. The latter shaft carries also a
pinion 50 which meshes continuously with a gear
51 secured to the drum shaft 51' carried by the
forward ends of the standards. The drum shaft 60
carries the drums 52 and 52' which are utilized
to wind and unwind the cables 53 and 53', the
cables being so attached to the respective drums
that when one winds on the other winds off.
The cables pass over the pulleys of the boom
65 and have their free ends supplied with snap
hooks 54 or other suitable fastenings. It will be
here observed that the drums can be rotated for-
ward or reverse, as desired, by manipulating the
lever 47 and that the chain wheel 42' is always
70 rotated in the same direction and that the opera-
tion of the hoist is controlled by the clutch under
the influence of the lever 49.

The driving unit 25 for the boring tool, is now
75 described in detail. A horizontally disposed plate

56 is securely fastened to two similar parallel underlying supports 57 and 57'. The plate carries two rearwardly disposed similar bearing standards 58' and 58^x which rotatably support 5
5 a rear cross shaft 58 and an adjoining counter-shaft 59. The ends of the cross shaft 58 are rotatably carried in the side plates 24 and 24' already referred to, such arrangement allowing the driving unit to be angularly adjusted by the 10
10 raising or lowering of the forward end thereof. To hold the unit in any adjusted position I have supplied the side beams or supports 57 and 57' with outstanding screw threaded studs 60 which protrude through slots 24^x supplied in the side 15
15 plates 24 and 24' and are provided with nuts 61 carrying a handle 61'. The slots are formed concentric to the shaft 58. The latter shaft is supplied with a chain wheel 62 and a pinion 62' and the chain wheel is connected by a chain 62^x 20
20 to the chain wheel 42^x previously mentioned.

The pinion 62' meshes continuously with a gear wheel 63' secured to the counter shaft 59. The countershaft carries centrally a worm 64 which is adapted to mesh with a worm wheel 65 25
25 having a square hole 65' centrally therein adapted to receive the upper square rod or section 26 of the line of rods leading to the boring tool. The worm wheel is provided at the top with a ball race 67 containing ball bearings 67' and has 30
30 the underside thereof fitted with a concentric channel 68 adapted to receive an upstanding centering flange 69 formed from the plate 56. It will be observed that the body of the plate is cut away to provide a circular opening 70 35
35 bordered by the flange and that a slot 70' extends from the opening to the front edge of the plate 56, the flange being omitted at the slot. This arrangement permits of the rod 26 being cleared forwardly from the machine through the 40
40 slot upon the worm wheel being lifted clear of the flange.

Provision is made for holding down the worm wheel when the same is working, and this comprises a yoke bar 71 centrally engaging the outer 45
45 circle of the ball race and centrally spanning the rod 26 and having one end pivotally mounted on a pin 72 carried by a vertical post 72' and the other end slotted at 71' to receive a pin 73 carried by a further post 73'. The pins are threaded to receive nuts 74 and 74' and the nut 74 is supplied with a handle 74^x for manipulating purposes. The posts are permanently carried by the plate 56. Obviously by releasing the nut 74 and swinging the yoke bar rearwardly, 50
50 one can raise the worm wheel to clear it from the flange and if desired can clear it also from the rod.

The boring tool 75 is of the same type as that described in the patent hereinbefore mentioned 55
55 and is fully shown in Fig. 12. The tool is rotated in the excavation by the line of similar rods all such rods being connected together and to the tool by similar universal joints. The joints are made so that they can be readily disconnected 60
60 to permit of the insertion of additional lengths of rods as the boring work proceeds. In Fig. 12^A I have shown the type of universal joint employed and here it will be seen that one can disconnect the ends of adjacent rods by removing the bolt B pivotally connecting one of the forks C to the X-shaped coupler D. The other of the forks E is pivotally connected to the coupler D by pivot studs F.

The machine is used as follows, it being understood that it is placed preferably at right 65
75

angles to the wall 76 underneath the footing 76' of which it is desired to place the concrete pier. An excavation 77 is previously made at the side of the wall down to the footing, and then a limited excavation is made at 77' under the footing this being deep enough to permit of the vertical placement of the boring tool 75 centrally under the footing. Several rods are then connected to the boring tool, the upper rod being passed upwardly through the square hole in the worm 10
10 wheel. The motor is then started and the attendant then actuates the lever 40 to engage the clutch and cause the driving of the shaft 29, which results in the driving of the shaft 58 through the chain 62^x. This latter shaft being driven, the worm wheel is driven in a direction to cause the line of rods to drive the boring tool down into the earth and as it lowers the upper rod slides downwardly through the worm 15
15 wheel. During this operation the gear 44 is in 20
20 neutral position so that the drums are idle. At the time of working the boom will be held in the raised position shown in dotted outline in Fig. 1 so that the cables are close to the outer face of the wall and can readily descend into 25
25 the excavation made by the tool, when required. When the upper end of the upper rod has descended to approximately the level of the top of the worm wheel, the lever 40 is thrown to neutral position and the boring operation accordingly stops. The yoke bar is then released and swung back and the worm wheel is removed from the upper end of the upper rod. The lever 47 is then shifted to bring the gear 44 into mesh with the pinion 42' and then the lever 49 to cause 30
30 the clutch 32 to engage and drive the drums, through the train of gears provided. As the drums rotate one cable moves up and the other down and when the attendant considers the down cable is properly located for load lifting 35
35 purposes he stops the drums by shifting the lever 47 to neutral position and proceeds to connect the down cable to one of the line of rods. Connection can be made by utilizing a split, spring grab ring 78 (see Fig. 13) which is supplied with 40
40 an offset portion 78' adapted to receive the rod and has the ends thereof connected by a short length of chain 78^x adapted to be caught in the snap hook 54. The split ring can be dispensed with however if desired as the snap hook 50
50 can be caught directly in one of the forks of the universal joint of one of the rods. After the down cable has been connected to the rod, which at such time is forward out of the slot 70', the attendant shifts the lever 47 to bring the gear 55
55 55 into mesh with the pinion 43 and this causes the up movement of the attached end of the latter cable and the down movement of the other cable. When the up moving cable has travelled sufficiently far to lift the boring tool and its 60
60 earth load to ground level, the clutch is released and the boom is swung to the side to dump position and the earth is cleared from the boring tool. I might here mention that the earth in this locality is of a clayish nature and clings to 65
65 the boring tool and requires to be removed from the tool by using a shovel. After the earth is cleared the next operation is to insert a further rod or section in the line and re-enter the tool and line in the bored hole. The upper end of 70
70 the line is re-entered in the slot 70' and the worm wheel is applied thereon and moved to its seated position on the centering flange. The yoke bar is then fastened in position over the worm wheel and the work of boring is again 75

proceeded with, in the same manner as already described. Each time the tool has descended approximately the length of the added line section it is lifted and cleared of earth and a new 5 section or rod is added to the line. The work is continued until a firm base is encountered and when this occurs the machine has finished its job. Thereafter the work of forming the concrete pier and associated operations is carried 10 on in the manner described in the patent hereinafter referred to.

I might here point out that the weight of the loaded tool can be supported at any time by throwing the clutch to the out position at which 15 time the inner face of the cone pulley 34 is frictionally engaged with the outer face of the adjacent standard 27' and the friction so developed acts as a brake to prevent any spinning of the intermeshed gears. I wish also to mention that 20 in the raising of the loaded tool from the hole, the cables are alternately used to lift the load, each cable raising the load approximately a distance equal to the length of a rod of the line. An attendant in the excavation 77' attends to the 25 attaching of the loose down cable to the successive rod joints where a grab or snap hook is used and an attendant on the ground disconnects the up cable. Where the split ring is used, it is passed downwardly over the underlying joint 30 after being released from the up cable and while the load is held suspended, and is then connected to the down cable when the lifting work is resumed.

In Figs. 15 and 16 I have shown a modification 35 of the machine and in this arrangement there is more weight placed forwardly. The hoist 9 has been shifted to the forward end of the frame with the drum to the rear and is mounted on an underlying plate 56 carried by two similar spaced 40 side members 79 corresponding to those 57 and 57' previously mentioned. The side members are pivotally connected to the main frame by side bolts 80 carried by side plates 80' bolted to the beams 2 and 2'. Side bars 81 are pivotally secured at 81' to the front ends of the beams 2 and 2' and such bars are adjustably connected to the side members 79 by bolts 89^x, suitably spaced 45 holes being provided in the side bars for adjustment purposes.

50 The worm shaft 52 of the boring tool driving unit 25 is rotatably mounted in the side standards 27 and 27' directly in advance of the countershaft 44' and the gear wheel 63' of the worm shaft is shown as meshed with the gear 41 of the hoist. The control levers have been dispensed with and instead the spindles 36 and 45 are supplied with hand grips 82 and 82'. The shaft 41' is driven directly by a belt 63 from the electric motor. The mast is shown as fixed to the 55 frame and has secured permanently thereto a somewhat elevated bracket 84 which carries the boom 12, the boom being connected to the bracket by a ball and socket joint indicated generally by the reference number 85.

60 The mast rotatably supports a cross shaft 86 carrying a pair of drums 87 and 87' and the cables 69 and 53' pass rearwardly from the drums of the hoist, under the pulleys 87 and 87' and then upwardly to the pulleys of the boom in the same 65 manner as before. When working, the modified type of machine is operated the same as before explained.

In Fig. 14 I have shown a pile weight or hammer 88 fitted at its upper end with an eye 88' and 70 this can be used with the hoist to drive piles in

the lower end of the bored hole when it is found desirable so to do. The weight will be attached to one of the cables by catching the snap hook in the eye 88'.

While I have described the invention in detail 5 it will be readily understood that various changes can readily be made without departing from the spirit of the invention as set forth in the accompanying claims.

What I claim as my invention is:—

10 1. In a device for manipulating an earth boring tool, a support having an open ended slot therein, a flexible tool driving line passing from the tool upwardly through the slot, a line driving wheel slidably receiving the line and rotatably carried by the support, said wheel being demountable from the support to permit of the freeing of the line from the support by a lateral movement through the slot and a source of power for driving the mounted wheel.

15 2. In a device for manipulating an earth boring tool, a support having an open ended slot therein, a flexible tool driving line passing upwardly from the tool and through the slot, a line driving wheel slidably receiving the line and rotatably carried by the support, said wheel being demountable from the support to permit of the freeing of the line from the support by a lateral movement through the slot, a hoist provided with a lifting cable for connecting to the freed line 20 and a source of power for selectively driving either the wheel or the hoist.

25 3. In a device for manipulating an earth boring tool, a support having an open ended slot therein, a flexible tool driving line passing upwardly from the tool and through the slot, a line driving wheel slidably receiving the line and rotatably carried by the support, said wheel being demountable from the support to permit of the 30 freeing of the line from the support by a lateral movement of the line through the slot, a hoist provided with winding on and winding off cables alternately connectable to the freed line, a prime 35 mover, a reversible driving connection between the prime mover and the hoist and a direct driving connection between the prime mover and the 40 wheel.

4. In a device for actuating an earth boring tool, a support having an open ended slot therein, a jointed, flexible, tool driving line extending 45 from the tool upwardly through the slot, a worm wheel slidably receiving the line and rotatably carried by the support, said wheel being demountable from the support to permit of the 50 freeing of the line from the support by a lateral movement of the line through the slot, a worm 55 carried by the support and engageable with the mounted worm wheel, a prime mover and a driving connection between the prime mover and the 60 wheel.

5. In a device for manipulating an earth boring tool, a support having an open ended slot therein, a jointed, flexible, tool driving line extending upwardly from the tool and through the 65 slot, a worm wheel slidably receiving the line and rotatably carried by the support, said wheel being demountable from the support to permit of the 70 freeing of the line from the support by a lateral movement of the line through the slot, a worm carried by the support and engageable with the mounted worm wheel, a hoist provided with winding on and winding off cables for alternate connection to the freed line, a prime mover, 75 a reversible driving connection between the prime

mover and the hoist and a direct driving connection between the prime mover and the worm.

6. In a device for manipulating an earth boring tool, a portable main frame having a slotted forward end, a flexible, jointed, tool driving line extending from the tool upwardly through the slot, a line driving, worm wheel slidably receiving the line and rotatably carried by the forward end of the frame, said worm wheel being demountable from the frame to permit of the freeing of the line from the frame, by a lateral movement of the line through the slot, a worm carried by the frame and engageable with the mounted wheel, a hoist mounted on the frame and providing a winding cable for connection with the freed line, a prime mover mounted on the frame, a reversible clutch controlled driving connection between the prime mover and the hoist and a non-reversible, clutch controlled driving connection between the prime mover and the worm.

7. In a device for manipulating an earth boring tool, a portable main frame, a tiltably mounted plate carried by the forward end of the frame, said plate being provided with an open ended slot, a flexible, jointed line connected to the tool and passing upwardly through the slot, a line driving worm wheel rotatably carried by the plate and slidably receiving the line, said wheel being demountable from the plate to permit of the freeing of the line from the plate by a lateral movement of the line through the slot, a worm rotatably carried by the plate and engageable with the mounted worm wheel, a hoist mounted on the frame and providing a winding cable for connection with the freed line, a prime mover mounted on the frame, a clutch controlled reversible driving connection between the prime mover and the hoist and a clutch controlled driving connection between the prime mover and the worm.

8. In a device for manipulating an earth boring tool, a portable main frame, a tiltably mounted plate carried by the forward end of the frame, said plate being provided with an open ended slot, a flexible, jointed line connected to the tool and

passing upwardly through the slot, a line driving worm wheel rotatably carried by the plate and slidably receiving the line, said wheel being demountable from the plate to permit of the freeing of the line from the plate by a lateral movement of the line through the slot, a worm rotatably carried by the plate and engageable with the mounted worm wheel, a hoist mounted on the frame and providing winding on and winding off cables for alternate connection to the freed line, a prime mover mounted on the frame, a clutch controlled direct driving connection between the prime mover and the worm and a reversible drive for the hoist, actuated by the prime mover and under the control of the clutch.

9. In an excavator, a main frame, a tiltable plate adjustably secured to the front end of the frame, and having an open ended slot therein, an earth boring tool, a jointed, flexible, driving line connected to the tool and passing upwardly through the slot, a wheel for driving the line, said wheel slidably receiving the line and being demountably centered, in working position, on the plate to permit, upon the dismounting of the wheel, of the removal of the line from the plate, through the slot, a releasable member normally engaging the wheel to prevent the lifting of the same, from working position, and means for driving the wheel in working position.

10. In an excavator, a main frame, a tiltable plate adjustably secured to the front end of the frame, and having an open ended slot therein, an earth boring tool, a jointed, flexible, driving line connected to the tool and passing upwardly through the slot, a worm wheel for driving the line, said wheel slidably receiving the line and being normally supported by and removeably centered for rotary movement, on the plate, a releasable, shiftable member normally overlying the wheel and clear of the line, and normally preventing lifting of the wheel from the plate, and a worm mounted on the plate and normally engaging with the worm wheel.

GEORGE E. BALDRY. 45
